UNITED STATES PATENT OFFICE.

KARL KRUG, OF FECHENHEIM, FRANKFORT-ON-THE-MAIN, GERMANY.

GRINDING-MACHINE.

1,102,344.

Specification of Letters Patent.

Patented July 7, 1914.

Application filed January 8, 1914. Serial No. 811,040.

To all whom it may concern:

Be it known that I, KARL KRUG, a subject of the Emperor of Germany, and resident of Fechenheim, Frankfort - on - the - Main, Germany, have invented a certain new and useful Improvement in Grinding-Machines, of which the following is a specification.

This invention relates to a grinding machine with separate supports for the work 10 and the grinding means.

In accordance with the invention provision is made for relative adjustment of the supports by means of tension or adjusting devices which are interposed between the 15 supports and by adjustment of which a bending moment in a vertical plane or a torsional moment in a horizontal plane may be set up in the work support or each work support so as to alter the position of the 20 upper end of the work support or each work support in relation to the support for the grinding means.

In the accompanying drawing Figure 1 is a side elevation of a grinding machine 25 embodying the invention; Fig. 2 is a front elevation thereof; Fig. 3 a section on the line A—B of Fig. 1; and Figs. 4 and 5 show, in detail, the means for the relative adjustment of the work and grinding spindle supports, on a larger scale.

As shown, the spindle *d* on the free ends of which are secured the face grinding disks *e*, is horizontally journaled in a support or frame *a* which is secured on a foundation on 35 which latter adjacent to said frame *a* are mounted separate work supports *b* carrying the adjustable work tables *f* which are as usual equipped with T-slots for the purpose of securing the work. Each work-support 40 *b* is provided adjacent to its lower end with a projection *b*¹ presenting a plane face opposed to a plane face on an adjoining projection *a*¹ on the frame *a*. The projections *a*¹ and *b*¹ are connected by means 45 of fastening screws *g* (Fig. 2). Each of the projections *a*¹ and *b*¹ is provided with a lug *m* or *m*¹ at its upper end and a lateral lug *o* or *o*¹. Threaded into corresponding lugs are adjusting screws *i* and *k* by adjustment 50 of which the supports *b* for the work

tables *f* may be adjusted relatively to the frame *a*.

It is clear that by the adjustment of the screw *i* after loosening the two upper fastening screws *g* on the same side of the frame 55 *a*, an inclination will be imparted to the corresponding work support *b* and the work table *f* will thereby be caused to approach or recede from the adjacent grinding disk *e* according to the direction of inclination; 60 the location of the work table in relation to the horizontal plane being simultaneously altered. By adjustment of the tension screw *k* a torsional moment is imparted to the support *b*, the work table *f* thus receiving 65 a rotary movement in its own plane, whereby the relationship of the edge of the table *f* adjacent to the grinding disk and the face of said disk is altered. The work table may thus be adjusted not only in the vertical plane including the spindle *d* but also in a substantially horizontal plane parallel to 70 said spindle. This result is attributable partly to the arrangement of the work tables upon supports which are independent 75 of the support for the grinding disks but mainly to the employment of the support for the grinding disks as an abutment for forces set up to effect the desired adjustments by deflection of the work supports. With the 80 described arrangement the stresses received by the frame *a* and the vibrations of the grinding disk are largely prevented from reaching the work tables *f* and thus an increase of precision in the grinding operations 85 is attained.

What I claim is:

1. In a grinding machine the combination with separate supports for the work and for the grinding means, of devices interposed 90 between said supports, said devices being adjustable one independent of the other to produce deflection and torsion of the work-support.
2. In a grinding machine the combination 95 of separate juxtaposed supports for the work and the grinding means, the adjacent faces of said supports having projections each formed with a pair of internally threaded lugs, the lugs of one pair registering 100

with the lugs of the other pair, and screws having right and left hand threads in engagement with said lugs, one set of said lugs and corresponding screw adapted to produce deflection and the other set with corresponding screw adapted to produce torsion of the work support.

In testimony whereof I have signed my name to this specification in the presence of two subscribing witnesses.

KARL KRUG.
